DESIGN.

J. D. BODLEY.
EWER.

No. 19,397.

Patented Nov. 5, 1889.

UNITED STATES PATENT OFFICE.

EDWIN J. D. BODLEY, OF BURSLEM, COUNTY OF STAFFORD, ENGLAND.

DESIGN FOR AN EWER.

SPECIFICATION forming part of Design No. 19,397, dated November 5, 1889.

Application filed October 11, 1889. Serial No. 326,733. Term of patent 7 years. Patented in England June 17, 1889, No. 127,192.

To all whom it may concern:

Be it known that I, EDWIN J. D. BODLEY, a subject of the Queen of England, residing at Burslem, Staffordshire, England, have invented and produced a certain new and useful Design for an Ewer, fully described and represented in the following specification, and the accompanying drawing, forming a part of the same, the said improvements having 10 been registered in England June 17, 1889, No. 127,192.

The leading or distinguishing features of the design are the shape of the ewer and the ornamental band which encircles its neck just 15 above the swell of the body, substantially as shown in the accompanying illustration.

Referring to said illustration, it will be seen that the body A of the ewer is substan-

tially round in horizontal section, and at a suitable height is contracted equally or substantially so on all sides, so as to form a neck B of suitable size. The neck B at its junction with the body is encircled by a raised band or collar C of ornamental design. The ewer is also provided with a handle D. 25

What I claim is—

The design for an ewer, substantially as herein shown and described.

In testimony whereof I have hereunto set my hand in the presence of two subscribing witnesses. 30

EDWIN J. D. BODLEY.

Witnesses:

J. H. COPESTAKE,
H. POOLE.
